INVENTOR

Martin Bretherton
BY John M. Diederich

ATTORNEY.

UNITED STATES PATENT OFFICE.

MARTIN BRETHERTON, OF HADDONFIELD, NEW JERSEY.

CUTTER OR TRIMMER FOR SHADES, &c.

SPECIFICATION forming part of Letters Patent No. 535,191, dated March 5, 1895.

Application filed December 23, 1893. Serial No. 494,534. (No model.)

To all whom it may concern:

Be it known that I, MARTIN BRETHERTON, a citizen of the United States, residing at Haddonfield, in the county of Camden, State 5 of New Jersey, have invented a new and useful Improvement in Cutters or Trimmers for Shades, &c., which improvement is fully set forth in the following specification and accompanying drawings.

10 My invention consists of a cutter or trimmer formed of a base and a movable stock, with an interposed spring or springs, a blade on said stock and guides for the device, the construction and operation of parts being 15 hereinafter set forth.

Figure 1 represents a perspective view of a cutter or trimmer embodying my invention. Fig. 2 represents a longitudinal vertical section thereof. Fig. 3 represents a transverse 20 section thereof on line x, x , Fig. 2.

Similar letters of reference indicate corresponding parts in the several figures.

Referring to the drawings: A designates the base of the cutter, and B designates a 25 vertically-moving stock which is supported on springs C, the latter being secured to the base A.

Rising from the ends and sides of the base 30 A are boxes D, which are open from above, and freely receive the corresponding portions of the stock A, the sides of the boxes having vertical slots E to receive the screws F which enter the stock, whereby the stock and base are connected, the stock is guided in its rising and falling motions, and said stock is limited in its ascent.

Depending from and secured to the stock at or about the center thereof are presser feet and ends G, which pass freely through the 40 base, and are adapted to bear upon the pile of shades or other articles to be cut or trimmed, and also rested against a rule H, as a guide, the device when in operation being supported on said rule.

45 On the stock B is a handle J, and a boss K, the latter having the blade or cutter L passed through it and being provided with a set-screw M, which is adapted to be tightened against said blade for holding the same in 50 vertically adjusted position.

In the base A is a throat N, through which

the point of the blade is adapted to protrude, so as to cut the articles below the same when the stock is lowered.

The operation is as follows: The base is 55 placed on the rule H, and the stock depressed, whereby the blade and presser feet are lowered, said feet pressing against the pile of articles and being placed alongside of said rule. The handle J is grasped, and the device advanced, whereby the blade cuts or trims the articles, while the feet ride on the edge of the rule, thus guiding the device true. When the cutting or trimming is effected, the stock is let go whereby it rises, and the knife and feet 60 return to their normal positions. It is not intended that the feet G shall press severely on the pile of articles, if at all, as they are designed in the main to be guided on their sides on the rule, while their lower edges run freely 65 on said pile, the main pressure on the pile being exerted by the rule on which the base A rests in the operation of the implement.

Having thus described my invention, what I claim as new, and desire to secure by Letters 70 Patent, is—

1. A base having a throat, a stock, a knife secured to said stock and adapted to pass through said throat, springs interposed between said base and stock, boxes connected 80 with said base and freely embracing said stock and screws which pass through vertical slots in the boxes into the stock, said parts being combined substantially as described.

2. In a cutter or trimmer substantially as described, a base, a stock, and a spring interposed between said base and stock, in combination with a vertical pressure foot and guide which depends from the stock and 90 freely passes through the base, substantially as described.

3. A cutter for the purpose named consisting of a base having a throat therein, a stock in said base, springs in said base and on 95 which said stock rests, a blade in said stock, guides and a handle for said stock, said parts being combined substantially as described.

MARTIN BRETHERTON.
